(57) CLAIM

The ornamental design for a pour over coffee maker, as shown and described.

DESCRIPTION

FIG. 1 is a top, front, right perspective view of a pour over coffee maker showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a top, front, right perspective view of the pour over coffee maker shown in use thereof;

FIG. 9 is a cross-sectional view of the pour over coffee maker of FIG. 6;

FIG. 10 is a top, front, right perspective view of the top portion of the pour over coffee maker of FIG. 1 shown separately for ease of illustration of the claim.

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom plan view thereof;

FIG. 17 is a top, front, right perspective view of the bottom portion of the pour over coffee maker of FIG. 1 shown separately for ease of illustration of the claim.

FIG. 18 is a front view thereof;

FIG. 19 is a rear view thereof;

FIG. 20 is a left side view thereof;

FIG. 21 is a right side view thereof;

FIG. 22 is a top plan view thereof; and,

FIG. 23 is a bottom plan view thereof.

The broken line showing in the figures is for the purpose of illustrating portions of the pour over coffee maker that form no part of the claimed design.

1 Claim, 23 Drawing Sheets
